INTERNAL COMBUSTION ENGINE

Filed May 28, 1927

BY *Otis D. Treiber* INVENTOR
Cyrus V. Anderson ATTORNEY

UNITED STATES PATENT OFFICE

OTIS D. TREIBER, OF NARBERTH, PENNSYLVANIA, ASSIGNOR TO TREIBER DIESEL ENGINE CORPORATION, OF CAMDEN, NEW JERSEY, A CORPORATION OF NEW JERSEY

INTERNAL-COMBUSTION ENGINE

Application filed May 28, 1927. Serial No. 194,888.

My invention relates to internal combustion engines of the Diesel type. More especially it relates to means for increasing the turbulence of the gases within the cylinder 5 between the head thereof and the piston which reciprocates in the cylinder.

It is desirable, in order that the highest efficiency may be attained, that when a liquid fuel is introduced into the cylinder of an 10 internal combustion engine, it be gasified before it contacts with the walls of the combustion chamber.

In the case of engines having cylinders of relatively small diameter, this is somewhat 15 difficult to accomplish, and the general object of the present invention is to provide an internal combustion engine with means whereby the liquid fuel introduced into the combustion chamber may be gasified before it contacts with the walls of said chamber.

It also is an object of the invention to provide means whereby the turbulence of the fluids within the combustion chamber may be greatly increased to thereby effect complete 25 intermingling of the air and the hydrocarbon gases produced as a result of the gasification of the liquid fuel introduced into the combustion chamber.

Other objects and advantages of the invention 30 will be pointed out in the detailed description thereof which follows or will be apparent from such description.

In order that the invention may be readily understood and its practical advantages fully 35 appreciated, reference may be had to the accompanying drawing in which I have illustrated one form of a convenient embodiment thereof.

In the drawing

40 Fig. 1 is a view in central vertical section of the upper portion of a cylinder with certain associated parts of an internal combustion engine, the piston being shown as approaching the head of the cylinder;

45 Fig. 2 is a similar view showing the piston after it has reached the limit of its outward movement in adjoining relation to the piston head;

50 Fig. 3 is a view similar to that shown in

Figs. 1 and 2 but showing the piston moving inwardly or away from the cylinder head;

Fig. 4 is a view in end elevation of the piston; and

Fig. 5 is a view in side elevation thereof.

55 In the drawing I have shown a cylinder 1 within which is mounted to reciprocate therein a piston 2. The cylinder is provided with the cylinder head 3 of known construction having the usual ports therein. I have shown 60 an air port 4 adapted to be opened and closed by means of a valve 5 actuated by means of a rod 6 connected at its outer end to a rocking lever 7 which in turn is actuated in any known manner. A spring 8 tends to hold the valve 65 5 in closed position.

For the purpose of injecting liquid fuel such as oil into the combustion chamber of the cylinder, I have provided an injection 70 nozzle 10 to which the fuel is supplied in any known manner through a pipe, one end portion of which is shown at 11.

75 The injecting nozzle is illustrated as projecting into the combustion chamber at a point located practically in the angle between a portion of the side wall of the cylinder and the cylinder head.

80 A corner portion of the crown of the piston is cut away to provide a flat surface as indicated at 15, which surface, when the piston is near or in its outermost position as shown in Figs. 1, 2 and 3 of the drawing, is located in opposed relation to the inner end of the injection nozzle 10. The surface 15 is provided with a depression or recess 16 85 at its center, which is of oblong shape, the major axis extending in a direction transversely of the piston and cylinder and substantially at right angles to the axes thereof. It will be noted that when the piston is in 90 its outermost position as shown in Fig. 2 of the drawing, the axis of the injection nozzle 10 is very nearly in alignment with the center of the depression or recess 16.

95 It will be seen that by the cutting away of a segmental portion of the piston 2 in the relation to the inner discharge end of the injection nozzle as shown, the point of injection of the liquid is located a considerable distance from the walls of the combustion 100

chamber. By thus providing means for locating the point of injection of the liquid fuel into the combustion chamber a considerable distance from the walls thereof as shown, the liquid is gasified before it contacts with the walls of said chamber. The efficiency of operation is thereby greatly enhanced.

The initial discharge or entry of the liquid fuel into the combustion chamber at each cycle of operation takes place when the piston occupies a position about eight degrees in advance of its dead center position; that is, the dead center position of the crank shaft to which the piston rod is connected. The injection or discharge of fuel into the cylinder continues until the piston has moved approximately eighteen degrees beyond its dead center position; that is, until the crank arm of the crank shaft has moved through an angle of approximately eighteen degrees beyond its dead center position.

In order to obtain the greatest possible thermal efficiency of the engine, it is necessary that the mixing of the hydrocarbons and the oxygen of the air be effected at the earliest possible moment after the injection of the liquid fuel into the combustion chamber.

In Fig. 1 of the drawing I have shown the piston in the position it occupies immediately after the injection of the liquid fuel into the combustion chamber is begun. The piston is traveling or moving outwardly or toward the head 3 of the cylinder. It will be understood that the required quantity of air has already been supplied to the combustion chamber through the port 4. It will be seen that as the piston approaches the cylinder head 3 the air within the cylinder above the piston 2 is caused to flow at a high rate of velocity to the right toward the chamber at the upper right hand corner of the cylinder, one wall of which is formed by the flat surface 15 and the recess or depression 16 therein. The air, with the oxygen contained therein, being driven with great force and rapidity strikes the liquid fuel or the hydrocarbon gases produced by the gasification thereof and becomes thoroughly intermingled therewith. A whirling motion will be produced. An attempt to indicate the motion by arrows 20 has been made.

When the piston begins its downward movement as indicated in Fig. 3 of the drawing, the turbulence of the gases within the combustion chamber is continued but the flow is then in a direction toward the opposite side of the combustion chamber, away from the point of discharge of the liquid fuel thereinto. An attempt has been made to indicate by arrows 21 in Fig. 3 the direction of the gas currents in the com-

bustion chamber as the piston makes its power stroke.

An attempt has been made also to indicate by arrows 22 in Fig. 2 of the drawing the direction of the whirling motion of the gases in the upper right hand corner of the combustion chamber at the approximate moment when the piston 2 has arrived in its outward movement at a point in contiguous relation to the cylinder head 3.

By my invention I have provided means whereby great turbulence of the gases within the combustion chamber is effected, which is sufficient to cause early, complete admixture of the oxygen of the air with the hydrocarbon gases produced by gasifying the liquid fuel, which results in an increase in the thermal efficiency of the engine.

Having thus described my invention what I claim and desire to secure by Letters Patent is:

An internal combustion engine comprising a cylinder and a piston adapted to operate in said cylinder, the crown of the said piston having a portion located in a plane substantially at right angles to the axis of said piston and a portion at one side thereof located in a plane forming an acute angle with said axis, the said last mentioned portion having therein a centrally located depression, the outer edge of which is flush with the remaining part of the surface of said portion, the said remaining part of the surface occupying a single plane.

In testimony that I claim the foregoing as my invention, I have hereunto signed my name this 27th day of May, A. D. 1927.

OTIS D. TREIBER.
